UNITED STATES PATENT OFFICE.

ALBERT T. HILAMAN, OF NEWARK, DELAWARE.

STOCK REGULATOR.

Application filed May 15, 1922, Serial No. 561,104. Renewed September 10, 1923.

To all whom it may concern:

Be it known that I, ALBERT T. HILAMAN, a citizen of the United States, residing at Newark, in the county of New Castle and 5 State of Delaware, have invented certain new and useful Improvements in Stock Regulators; and I do declare the following to be a full, clear, and exact description of the invention, such as will enable others 10 skilled in the art to which it appertains to make and use the same.

This invention relates to an improved stock regulator for use in connection with paper machines and one object of the invention is to provide the stock regulator with improved means for controlling feeding of the stock and to further provide improved means for preventing splashing of the pulp against the sides of the spout leading to the 20 pulp bucket and also prevent splashing of the pulp against the sides of the upper portion of the pulp bucket.

Another object of the invention is to provide improved means for controlling upward and downward movement of the pulp bucket and to provide an improved type of gate for controlling passage of the pulp through the gate leading from the pulp box, into the spout leading to the pulp bucket, 30 this gate being adjustably connected with a cross bail carried by arms from which the pulp bucket is suspended.

Another object of the invention is to provide an improved arrangement of parts for controlling rotation of a shaft carrying the 35 arms from which the pulp bucket is suspended so that the pulp bucket may be normally retained at a desired point but permitted of vertical movement either upwardly or downwardly as the amount of pulp in the bucket varies.

Another object of the invention is to provide an improved gate for controlling passage of the pulp.

Another object of the invention is to provide a stock regulator which will be very efficient in operation and simple in construction.

This invention is illustrated in the accompanying drawings, wherein:

Figure 1 is a view showing the stock regulator principally in side elevation and partially in vertical section.

Figure 2 is a vertical sectional view taken 55 along the line 2—2 of Fig. 1.

Figure 3 is a top plan view of the improved stock regulator.

Figure 4 is a transverse sectional view taken along the line 4—4 of Fig. 1.

This improved stock regulator is provided 60 with a pulp box 1 having therein an auxiliary chamber 2 provided with an inlet opening 3 and having communication with the interior of the pulp box 1 through an opening controlled by a gate 4. The pulp in the pulp box 1 is to pass out through a passage in the front wall of the pulp box and through a discharge pipe 5. This discharge pipe 5 is rectangular in cross section and adjacent its free end has its bottom wall cut 70 short to provide a discharge passage 6 through which the pulp may pass into the depending spout 7 which is secured to the free end portion of this pipe 5. This pipe 5 is provided in its upper wall with a passage 8 through which extends a gate 9 and within the pipe 5 against the side walls thereof, there has been provided guide strips 75 10 so that movement of the gate 9 will be controlled. The head 11 at the end of the pipe 5 is mounted for movement into and out of a closing position by means of the rivets 12 and a handle 13 is provided so that this head 11 may be easily swung into and out of a closing position. An apron 14 80 which is called a splash apron is pivotally mounted at its upper end within the pipe 5 and has its free end portion extending downwardly through the discharge passage 6 of this pipe. Therefore, as the pulp passes through the pipe 5 beneath the gate 9, this apron 14 will be swung to permit the pulp to pass downwardly into the spout 7 but will prevent this pulp from striking against the walls of the spout where it would tend to 85 adhere and add additional weight to the spout and prevent proper operation of the device. This spout 7 is rectangular in cross section and preferably oblong and is provided at its lower end with a closure plate or 90 head 15, the walls of the spout 7 being provided with discharge openings 16 adjacent the head 15 so that the pulp will pass from this spout through the side openings 16. It is desired to prevent this pulp from striking 95 against the upper portions of the walls of the pulp bucket 17 where it might adhere and give the bucket added weight and therefore there has been provided a hood 18 which fits upon the spout 7 and is secured 100 110

thereto by means of brackets 19. It will be readily seen that as the pulp passes through the discharge openings 16, it will strike the hood 18 and will drop directly into the bucket 17 upon the mass of pulp already in the bucket.

This bucket is to be suspended so that it may have vertical movement in case the quantity of pulp in the bucket should vary and the gate 9 is to be connected with the structure for mounting the bucket so that as the bucket moves vertically, the gate 9 may be moved towards an open or a closed position. The gate moves to an open position when the quantity of pulp is reduced beyond the normal amount so that more pulp can pass into the bucket than under normal conditions and the gate is to move towards a closing position so as to reduce the quantity of pulp passing through the spout 7 in case the bucket contains more than the normal amount of pulp. This bucket 17 is provided with hanger bars 20 which are secured to the bucket 17 adjacent its upper end and extend upwardly and are provided at their upper ends with bearing eyes 21 which extend between the hinged ears 22 at the forward end of the lever arms 23 and are secured by pivot pins 24 at the ends of the cross bar 25 which extends between the forward ends of the lever arms. This cross bar which serves to pivotally connect the hanger arms 20 with the lever arms 23 is provided intermediate its length with a passage 26 through which extends the threaded stem 27. This stem 27 is loosely connected with the gate 9 as shown at 28 and carries nuts 29 for engaging the upper and lower faces of the cross bar 25 and securely but adjustably holding the stem in a desired position with the gate 9 open the desired amount. It will thus be seen that the gate may be set at the proper point to permit a predetermined amount of pulp to normally feed through the pipe 5 into the spout 7 and retain the pulp in the bucket 17 at the normal level. The lever arms 23 are carried by a shaft 30 which is journaled in bearings 31 carried by the pulp box 1 and these arms extend rearwardly over the pulp box and carry weights 32 which are adjustable upon the arms so that they can exert the desired amount of leverage. It has been found that the hanger means cannot be properly adjusted by means of the weights 32 alone and therefore there has been provided a handle bar 33 which carries an adjustable weight 34 and in addition to the handle bar, there has also been provided a mast formed by bars 35 which extend upwardly in converging relation from the shaft 30 and have their upper ends connected by a pin 36 which carries a block 37. This block 37 which is loose upon the pin 36 carries a cable 38 which extends rearwardly and over

the pulley wheel 39 carried by the support 40. A weight 41 is carried by this cable 38. It will thus be seen that the bucket 17 will be normally retained in a desired position and that vertical movement of the bucket will be controlled by the weights 32, 34 and 41. The leverage exerted by the weight 41 cannot be changed but the leverage exerted by the weights 32 and 34 can be changed by adjusting these weights upon the arms 75 23 and 33.

In order to control passage of the pulp out of the pulp bucket 17, there has been provided an outlet spout having an upper bucket engaging section 42 and a lower section 42' which are secured together by bolts 43. The upper section 42 is reduced to provide a seat 44 in which is slidably mounted a gate 45 which extends between the forward portions of the two sections 42 and 42' and has its outer end portions provided with a depending fork portion 46 which engages an annular groove formed in the hub 47 of the adjusting wheel 48. This wheel 48 is mounted upon the threaded stem 49 which extends from the lower section 42' and it will be readily seen that when the wheel is rotated, the gate may be moved towards an open position or towards a closed position. A neck 50 is carried by the lower section of the collar formed by the two sections and extends downwardly into a pipe 51 through which the pulp will pass to the paper machine. The pulp can therefore pass freely into this pipe 51.

When in use, the pulp passes from the pulp box 1 through the pipe 5 and beneath the gate 9. After passing beneath the gate 9, the pulp moves the apron 14 to an open position and drops down through the spout 7 until it strikes the bottom or head 15 of this spout. The pulp then passes out through the discharge head 15 and down into the pulp bucket which will be filled to the normal capacity. This normal capacity in the present illustration is indicated at 52 but it will be understood that the normal capacity may vary. By turning the hand wheel 38, the gate 45 may be opened the desired amount so that the pulp may pass through the neck 50 and down into the pipe 51 through which it will pass to the paper forming machine. As the pulp flows out of the bucket, it will be replenished by the pulp flowing into the same through the spout 7. If the pulp flows into the bucket at a slower rate of speed than it passes out through the gate, the amount of pulp in the bucket will decrease beyond the normal amount and therefore the weight will be reduced. The weights 32, 34 and 41 will then cause the bucket to move upwardly and as this bucket moves upwardly, the gate 9 will move upwardly to permit an additional amount of pulp to pass through the spout 7 130

and increase the amount of pulp in the bucket until it has reached the normal capacity. It will thus be seen that the pulp will be kept at the normal level. Of course, if 5 the pulp is feeding too rapidly, the extra pulp in the bucket will give added weight so that the bucket will move downwardly and the gate 9 moved to a closed position thus reducing the amount of pulp fed into 10 the bucket. Therefore, the device can be set to permit the pulp to flow into the pipe 51 at the normal rate of speed and the pulp will be retained in the bucket at the normal level and fed properly into the pipe.

15 I claim:

1. In a structure of the character described, a stuff box, an outlet pipe for the stuff box having a depending spout, a gate in the pipe slidable upwardly to an open 20 position, a pulp bucket positioned about the lower portion of the spout and having an outlet in its lower portion and a control for the outlet, the spout having its lower end closed and provided with side openings, a 25 splash hood secured about the lower portion of said spout to direct pulp passing through the side openings downwardly into the bucket, and means for suspending the bucket for vertical movement and imparting movement to the gate of the outlet spout as the 30 bucket moves.

2. The structure of claim 1 having the bucket provided with an open lower end, a collar secured about the open lower end of 35 the bucket and having an upper bucket engaging section and a lower section secured to the upper section, the sections having registering central openings, a closure plate slidable between said sections, a threaded 40 stem extending from the lower section, a hand wheel upon said stem having a hub extension engaged by said closure plate whereby rotation of said wheel may impart sliding movement to the closure plate.

45 3. In a structure of the character described, a stuff box, an outlet pipe for the stuff box having a depending spout, a gate in the pipe slidable upwardly to an open position, a pulp bucket positioned about the lower portion of the spout and having an outlet in its lower portion and a control for the outlet, hanger arms extending upwardly from the bucket, a rotatably mounted rocker shaft, lever arms carried by the rocker shaft, 50 a cross bar extending between the lever arms and pivotally connecting the hanger arms with the same, a threaded stem pivotally connected with said gate and adjustably held in engagement with the cross bar, 55 weights adjustably carried by the lever arms, crane arms extending upwardly from said rocker shaft, a support carried by said stuff box and provided with a pulley wheel, a weight carrying cable connected with the 60 crane arms and engaged with said pulley, a

handle arm carried by said rocker shaft, and a weight adjustable upon said handle arm.

4. In a structure of the character described, a stuff box, an outlet pipe leading from the stuff box and having a closed free 70 end and having its under portion provided with a pulp passage adjacent the closed end, a gate slidable in said pipe adjacent the pulp passage and extending through the upper portion of the pipe, a splash apron in the 75 pipe pivoted at its upper end and having its lower end portion extending through the pulp passage, a depending spout carried by the free end portion of said pipe, a pulp bucket positioned about the lower portion 80 of the spout, and hanger means suspending the bucket for vertical movement and having connection with the gate of said outlet pipe for moving the gate into and out of a closed position as the bucket moves vertically.

5. The structure of claim 4 having the depending spout provided with a head at its lower end and outlet openings in its walls 90 adjacent said head, and a splash hood secured about said spout above the outlet openings and having depending walls extending below the lower end of the spout.

6. In a structure of the character described, a stuff box having an outlet in one 95 wall, an outlet pipe leading from said opening, a depending spout carried by the pipe and having a closed lower end and outlet openings in its walls adjacent the closed lower end, the outlet pipe having its under 100 portion cut away to permit of communication with said spout, a pulp bucket positioned about the lower portion of said spout and having an outlet in its lower portion and a closure for the outlet, a hood secured 105 to said spout above the outlets in the sides thereof and open at its lower end, the walls of the hood extending in spaced relation to the spout to a point below the lower end of 110 the spout, means for suspending said bucket and permitting vertical movement, and a gate for controlling passage of pulp through the outlet pipe, said gate being operatively connected with said bucket, suspending 115 means for movement into and out of a closed position as the bucket moves vertically.

7. In a structure of the character described, a stuff box having an outlet in one wall, an outlet pipe leading from said opening, a depending spout carried by the pipe and having a closed lower end and outlet openings in its walls adjacent the closed lower end, the outlet pipe having its under portion cut away to permit of communication with said spout, a gate slidable in the outlet spout and extending through the upper portion thereof, a pulp bucket positioned about the spout and having an outlet in its lower portion and a manually controlled gate for the outlet, hanger means for the 120 125 130

- bucket permitting vertical movement of the bucket and including means for yieldably holding the bucket against downward movement, and means connecting the gate of the 5 outlet pipe with the hanger means to cause opening and closing of the gate as the pulp bucket moves vertically.
8. In a structure of the character described, a stuff box having an outlet in one 10 wall, an outlet pipe leading from said opening, a gate in said pipe movable upwardly to an open position, a pulp bucket, movable means suspending the bucket below said pipe and connected with said gate to open and 15 close the gate as the bucket moves vertically, a collar carried by the lower end portion of said bucket, a gate slidably carried by the

collar and movable transversely thereof into and out of a closed position, and manually operated means for moving the last mentioned gate. 20

9. The structure of claim 8 having the collar provided with an upper bucket engaging section and a lower section connected with the upper section, the gate being slidably mounted between said sections and extending externally thereof, a threaded stem extending from one section, a hand wheel in threaded engagement with said stem, and means for engaging said wheel extending 25 from said gate.

In testimony whereof I have hereunto set my hand.

ALBERT T. HILAMAN.
